[57] CLAIM

The ornamental design for a fishing lure, as shown and described.

DESCRIPTION

FIG. 1 is a perspective view of a fishing lure showing my new design;

FIG. 2 is another perspective view of the embodiment of FIG. 1;

FIG. 3 is a bottom plan view of the embodiment of FIG. 1;

FIG. 4 is a top plan view of the embodiment of FIG. 1;

FIG. 5 is a side elevational view of the embodiment of FIG. 1 showing the proximal end of the preferred embodiment;

FIG. 6 is a side elevational view showing the distal portion of the embodiment of FIG. 1;

FIG. 7 is a front elevational view of the embodiment of FIG. 1; and,

FIG. 8 is a rear elevational view of the embodiment of FIG. 1.

The broken line showing of environment and all views is for illustrative purposes only and forms no part of the claimed design.
